TAMPING MACHINE

Joseph J. Hasch, 516 Bush Hill Road,
Manchester, Conn. 06040
Filed Mar. 23, 1965, Ser. No. 442,129
2 Claims. (Cl. 141—73)

This invention relates to powder filling and tamping devices, and more particularly to an improved tamping device for filling and tightly tamping bronze, silver, or similar types of powders into the confines of a relatively fragile retainer without breakage of said container.

The main object of the invention is to provide a novel and improved tamping machine which is relatively simple in construction, which provides an accurately controlled filling and tamping action, whereby powdered material, such as bronze, silver or similar powdered substances may be admitted into and tamped within a relatively fragile retainer without risk of breakage of the retainer, and which is operated pneumatically from a suitably timed air supply.

A further object of the invention is to provide an improved powder filling and tamping device for filling and tightly tamping bronze powder, silver powder, or other similar types of powder into carbon brushes, the machine being relatively inexpensive to fabricate, being durable in construction, and being self-clearing in action so that it is not easily clogged by the material being processed.

A still further object of the invention is to provide an improved powder filling and tamping device for filling and tightly tamping powders into suitable containers, the device being able not only to fill and tamp material into an unfilled cavity, but to continue to fill and tamp, with equal force, a partially filled cavity, the device continuing to tamp with substantially unchanging force even though the length of its plunger stroke continues to be reduced as the height of the tamped material in the container or cavity increases, whereby the material is substantially uniformly packed in the container or cavity and whereby the tamping force is always sufficient to provide uniform packing density of the material but is never high enough to cause breakage of the receptacle in which the material is packed.

Further objects and advantages of the invention will become apparent from the following description and claims, and from the accompanying drawings, wherein:

FIGURE 1 is a perspective view of an improved powder filling and tamping machine constructed in accordance with the present invention.

FIGURE 2 is an enlarged vertical cross sectional view taken substantially on the line 2—2 of FIGURE 1.

FIGURE 3 is a vertical cross sectional view taken through a modified form of powder filling and tamping machine in accordance with the present invention.

FIGURE 4 is a horizontal cross sectional view taken substantially on the line 4—4 of FIGURE 3.

FIGURE 5 is a fragmentary vertical cross sectional view of the lower portion of the machine shown in FIGURE 3 with the plunger element thereof in depressed tamping position.

Referring to the drawings, and more particularly to FIGURES 1 and 2, 11 generally designates an improved powder filling and tamping device constructed in accordance with the present invention. The device 11 comprises a support 12 consisting of a horizontal base plate 13 to which is rigidly secured an upstanding vertical supporting post 14. The post 14 rigidly supports a vertical sleeve 15, the sleeve being integrally connected to the post by a pair of spaced horizontal supporting bars 16, 16, whereby the sleeve 15 is rigidly sustained in spaced parallel relationship to the upstanding vertical post member 14, as is clearly shown in FIGURE 2.

2

Adjustably secured within the sleeve 15 is a cylindrical hopper 17, the hopper being secured in adjusted position in the sleeve 15 by a manually operated wing screw 58 threadedly engaged in the sleeve 15 and being clampingly engageable with the cylindrical body 17. Secured to the lower end of the cylindrical body 17 is a downwardly convergent conical spout member 18 in the end of which is secured an annular discharge nozzle element 19. The top portion of the cylindrical body 17 is integrally formed with an upwardly flaring peripheral flange 20 serving to guide material admitted into the top of the hopper downwardly through apertures 21 formed in a horizontal top wall 22 provided inside the hopper at the top end of its cylindrical body 17. The lower portion of said cylindrical body is similarly formed with a horizontal partition wall 23 formed with apertures 24 through which the material, shown at 25, may pass downwardly by gravity into the conical spout member 18.

Designated at 26 is an axial sleeve which is provided inside the body 17, said sleeve being formed integrally with and being supported by the top and bottom partition walls 22 and 23, as is clearly shown in FIGURE 2. Designated at 27 is a conventional air hammer which is provided with a reciprocating plunger 28, said plunger extending through the sleeve 26 and being slidably supported therein by spaced annular bushings 29 and 30 secured to the sleeve 26. As shown in FIGURE 2, the bushings 29 and 30 are spaced vertically sufficiently to guide the plunger 28 for axial reciprocating movement in the sleeve 26. The bushings 29 and 30 are secured in fixed positions in the sleeve 26 by set screws 31 and 32 threadedly engaged through the wall of sleeve 26 and clampingly engaging the bushings 29 and 30.

The air hammer 27 is provided with the downwardly tapering lower barrel portion 33 which extends into the top end of the sleeve 26 and which is rigidly secured thereto, as by welding, brazing, or the like, as shown at 34. Secured on the downwardly tapering member 33 is an annular outwardly extending upwardly diverging skirt member 35 provided with the upstanding peripheral flange 36, the skirt member 35 overlying the powder intake chamber defined by the upwardly flaring top member 20 of hopper 17.

Threadedly secured on the lower end of the sleeve member 26 is an annular cup member 37 having a central bottom aperture through which projects the reduced, rod-like lower end portion 38 of plunger member 28. The plunger member 28 is formed with an annular bearing flange 39 at the top end of reduced portion 38, and a coiled spring 40 surrounds said reduced portion, bearing between the flange 39 and the bottom wall of the cup member 37, biasing the plunger 28 upwardly. Thus, as shown in FIGURE 2, the spring 40 biases the plunger member 28 upwardly to a position wherein the lower end of the reduced plunger portion 38 is spaced above the top end of the central bore of the nozzle member 19, allowing powder material 25 in hopper 17 to gravitate downwardly through the nozzle. The base plate 13 supports a block 41 which is provided with a socket or recess 42 arranged so that it is in axial alignment with the nozzle 19, said socket 42 being adapted to receive a relatively fragile powder receptacle 43, such as a hollow carbon brush, as illustrated in FIGURE 2, thus positioning the receptacle immediately beneath the nozzle 19 to receive powdered material, such as copper or silver powder, therefrom. The bore 44 of the receptacle 43 is thus positioned in registry with the bore of the nozzle 19 and immediately subjacent thereto, as shown in FIGURE 2.

The air hammer 27 is of a conventional type wherein compressed air from a supply hose 45 is introduced into the upper portion of the barrel 46 of the air hammer and forces the air hammer plunger 28 downwardly until an

exhaust port (not shown) is opened, at which time air flows through the exhaust port and also through the center of the plunger downwardly and underneath a portion of the plunger so as to return it upwardly and to close the exhaust port. The air hammer 27 therefore operated on a "flutter" principle, and its rate of reciprocation depends on the pressure of the air supplied thereto and on the natural resonance of the plunger mass operating against the compliance of the compressible air. The air hammer 27 in itself is a well known conventional device and the details thereof form no part of the present invention.

In operation, the powdered material 25 gravitates downwardly into the bore 44 of the receptacle 43, to fill same. Air is then admitted to the air hammer 27, causing the plunger 28 to be moved downwardly into tamping engagement with the powder in the receptacle 43, the air supply being timed suitably so as to provide a sufficient number of reciprocations of the reduced plunger portion 38 to compress the material contained in the receptacle bore 44 to a desired density. It will be seen that the recess or socket 42 in the plate member 41 supports the receptacle for a substantial portion of its height and serves as a means for absorbing the compression developed therein by the tamping action of the reduced plunger member 38. Thus, the receptacle 43, even if made of relatively frangible material, is protected against breakage.

Uniform density of the material contained in the receptacle 43 is achieved even though the air hammer 27 is of the rapidly acting type working on a "flutter" principle; this type of air hammer has to have a stroke length of substantially constant amplitude applied against a substantially constant load in order for it to continue to function. In the apparatus of FIGURE 2, the spring 40 presents a load which changes with stroke length, the spring load cooperating with the load presented by the material being tamped to provide the required substantially constant load on the air hammer. Thus, effective tamping action is achieved within the fixed frame of the machine over a very considerable range of stroke length.

As will be readily understood, when the material in the receptacle 43 has been sufficiently tamped, the air supply may be discontinued, and the spring 40 then elevates the plunger 28 to its uppermost position. The container 43 may then be removed and another container may be substituted therefor so that the tamping process may be repeated.

The plate member 41 may be removable so that after the material in a container 43 has been suitably tamped, the plate member 41 may be removed so that the filled container 43 may be replaced by an empty one, or alternatively, another plate member 41 containing an empty container 43 may be placed into tamping position on the base supporting plate 13.

As will be readily apparent, the flange 39 may be integral with the element 38, and may be separate from the plunger 28, the spring 40 acting to bias the flange 39 against the bottom end of the plunger 28, and the plunger 28 operating to transmit repetitive hammer blows to the flange 39, which are in turn transmitted to the tamping element 38.

FIGURES 3, 4 and 5 illustrate a form of the invention wherein the tamping element, shown at 38' is separate from the air hammer plunger element 28', as above suggested. As shown in FIGURE 3, the tamping element 38' may be formed with an annular flange 50 at its upper portion, and a coiled spring 51 may be provided, bearing between the flange 50 and the upper bearing bushing 29, the spring 51 surrounding the top end portion of the hammer element 38' and the lower portion of the plunger member 28'. The spring 51 is relatively light and is yieldable to the main biasing spring 40 which bears between the bottom wall of the cup member 37 and a washer 52 surrounding the downwardly tapering shoulder 53 formed on the intermediate portion of the tamping element 38'.

The lower portion of the tamping element 38' comprises a reduced rod-like element 54 which extends through the central aperture in the bottom wall of the cup member 37 and which is slidably receivable in the bore of the nozzle member 19' provided at the bottom end of the downwardly converging spout element 18'.

As in the previously described form of the invention, a plate 41' is provided, said plate being formed with a socket or recess 42' which receives a flanged receptacle 43'. The receptacle 43' is formed with a central axially extending cavity 44' which is registrable with the bore of the nozzle element 19', as shown in FIGURE 3, and which receives the powdered material 25. As in the previously described form of the invention, the powdered material is tamped in the cavity 44' to a desired density by the reciprocating hammer action of the rod-like tamping element 54 as the element reciprocates downwardly through the bore of the nozzle 19', the rod-like member 54 descending on its downward stroke to a position such as that illustrated in FIGURE 5, wherein the rod-like element enters the top portion of the cavity 44' and is slidably received therein, exerting a downward compressive stroke on the material 25 contained in the cavity 44'. With each downward hammer stroke the spring 40 is compressed, as shown in FIGURE 5, said spring acting to elevate the plunger member 38' with each release stroke of the air hammer plunger member 28'. The spring 40 thus acts essentially in the same manner as in the embodiment of FIGURES 1 and 2 to cooperate with the load presented by the tamped powder to maintain a substantially constant load on the air hammer for different stroke lengths, and also acts to maintain the top end of the tamping member 38' substantially in continuous engagement with the bottom end of the plunger member 28', the spring 51 providing a cushioning action to compensate for the differences in inertia between the reciprocating elements 28' and 38' and to insure smooth and substantially synchronous reciprocation of these elements.

While certain specific embodiments of an improved powder filling and tamping machine have been disclosed in the foregoing description, it will be understood that various modifications within the spirit of the invention may occur to those skilled in the art. Therefore, it is intended that no limitation be placed on the invention except as defined by the scope of the appended claims.

What is claimed is:

1. A powder filling and tamping machine comprising a support, a tamping receptacle on said support, a downwardly convergent hopper on said support having a bottom discharge aperture located over said receptacle, said receptacle being located immediately below said bottom discharge aperture, a central tubular vertical supporting sleeve rigidly secured in said hopper and having a centrally apertured bottom wall in vertical alignment with and spaced above said discharge aperture, a vertically reciprocable plunger mounted in said supporting sleeve in vertical alignment with and being slidably engageable in said discharge aperture, pneumatically operated reciprocating means acting on said plunger and having a stroke of sufficient length to cause the plunger to engage in said discharge aperture during the bottom portion of said stroke, an annular bearing member on the upper portion of said plunger, said sleeve having an annular cup member on its bottom end, and spring means contained in said annular cup member and bearing between the bottom end portion of said annular cup member and said annular bearing member and biasing the plunger upwardly toward a position wherein its bottom end is above said discharge aperture and presenting a load to the plunger which increases with downward movement of the plunger, whereby said spring means cooperates with material being tamped in said receptacle to present a substantially constant load to the plunger for different stroke lengths.

2. A powder filling and tamping machine comprising

a support, a tamping receptacle on said support, a downwardly convergent hopper on said support having a bottom discharge aperture located over said receptacle, said receptacle being located immediately below said bottom discharge aperture, a central tubular vertical supporting sleeve rigidly secured in said hopper and having a centrally apertured bottom wall in vertical alignment with and spaced above said discharge aperture, a vertically reciprocable plunger mounted in said supporting sleeve in vertical alignment with and being slidably engageable in said discharge aperture, pneumatically operated reciprocating means acting on said plunger and having a stroke of sufficient length to cause the plunger to engage in said discharge aperture during the bottom portion of said stroke, an annular bearing member on the upper portion of said plunger, said sleeve having an annular cup member on its bottom end, and a coiled spring contained in said annular cup member and surrounding the plunger below said annular bearing member and bearing between the bottom end portion of said annular cup member and

5 said annular bearing member and biasing the plunger upwardly toward a position wherein its bottom end is above said discharge aperture, said spring presenting a load to the plunger which increases with downward movement of the plunger, whereby said spring cooperates with material being tamped in said receptacle to present a substantially constant load to the plunger for different stroke lengths.
